CENTRIFUGAL MACHINE FOR CONTINUOUS OPERATION

Ernst Rüegg, Kusnacht, Switzerland, assignor to
Escher Wyss Aktiengesellschaft, Zurich, Switzerland, a corporation of Switzerland

Application August 20, 1951, Serial No. 242,737

Claims priority, application Switzerland
September 2, 1950

6 Claims. (Cl. 210—68)

1

The invention relates to a centrifugal machine for continuous operation comprising a separator cage, a feed pipe delivering the material to be centrifuged to the said cage and a pusher member moved axially in relation to the separator cage.

In known centrifugal machines of this type, which are generally called "push-type centrifuges," the feed pipe is stationary and discharges into an inlet funnel secured to the pusher member, which is fashioned as a disc and rotates with the separator cage.

The endeavor is to charge push-type centrifuges continuously in a uniform manner and to a maximum extent, that is to say, to utilise the machine as fully as possible. This is done in order to obtain economical operation and a discharge as uniform as possible and thus to obtain material of uniform as possible a quality. Variations in the quantity of material fed to the cage necessarily involve fluctuations in the quantity of discharged material and consequently variations in the period for which the solid material remains in the cage, which in turn affects the degree of dryness of the discharged centrifuged material. If the variations in the quantity of material fed into the machine are particularly great, this may even lead, if the material to be centrifuged is of a particular nature, to a hardening of the cake and to the formation of incrustations on the cage and on its sieve.

The differences in the quality of the discharged centrifuged material are particularly noticeable if it must also be washed in the cage, since the washing naturally always takes place with a constant quantity of liquid, so that variations in the quantity of material pushed through the cage lead to unevenly washed material.

Moreover, the method so far used for introducing the material to be centrifuged into the centrifugal cage, which is generally constructed as a perforated drum, and according to which the feed pipe leads into the open inlet funnel entails a considerable circulation of air in the rotating parts, especially in the inlet part of the machine. Thus, the inlet funnel sucks in air through the gap between its inlet aperture and the tubular feed pipe and this air is ejected for the greater part radially through the perforated cage and partly axially through the cake of centrifuged material. The partial pressures thus set up cause after-crystallisations in the centrifuged material, which results in hardening therein and in the formation of incrustations and obstructions in the sieves. Such incrustations are

2

formed especially when centrifuging warm or hot materials, which undergo a forced cooling owing to the said air circulation.

In order to achieve the aforesaid objects while avoiding the disadvantages mentioned, in a centrifugal machine according to the invention the feed pipe is introduced into the distribution chamber of the centrifugal machine in gas-tight and liquid-tight manner and is furthermore so constructed that part thereof can follow the relative axial movements of the pusher member in relation to the cage of the sieve-filter type.

In a centrifugal machine according to the invention the feed may be effected under pressure, so that the feed pipe and the filling funnel are constantly partially filled with the mixture to be centrifuged. During the working stroke of the push-disc the flow in the feed pipe stops, but automatically re-commences when the push-disc effects its return stroke. The rigidity of the cake of solid material deposited on the perforated cage and the seal thereby effected at the passage from the inlet funnel into the drum prevent an unintentional emptying of a storage container provided for feeding the centrifugal machine with material to be centrifuged.

Various embodiments of the subject of the invention are illustrated by way of example, in simplified form, in the accompanying drawings, in which:

Fig. 1 shows an axial longitudinal section through a first form of construction, and

Fig. 2 shows an axial longitudinal section through a form of construction in which an inserted structure and a discharge pipe for liquid separated in a chamber between the inlet funnel and the inserted structure are provided in combination with the inlet funnel.

Fig. 3 shows an axial section through a third form of construction, in which an inserted structure is also provided, and in addition a receiving chamber for centrifuging material which passes through a stuffing box provided at the point of introduction of the feed pipe into the inlet funnel.

Fig. 4 shows an axial longitudinal section through a fourth form of construction in which part of the feed pipe is pivotally mounted on the machine housing, while

Fig. 5 shows partially a view in the direction of the arrow A of Fig. 6 and partially sections through parts of a fifth form of construction, and

Fig. 6 shows a section on the line VI—VI of Fig. 5.

In cases where the parts have an identical

action to those of Fig. 1, they have been provided with corresponding reference numerals in the various figures.

In Fig. 1, 1 is the cage of a push-type centrifuge. This cage 1 is of the sieve-filter type and it is rigidly connected through a disc 2 to a driving shaft 3 constructed as a hollow shaft. The driving shaft 3 has a portion widened out to form a cylinder 4. A rotational movement is imparted by an electric motor 3¹ and a belt driving 3² to the parts 1, 2, 3 and 4, which form a rotor. Housed in the cylinder 4 is a displaceable piston 5 which engages by means of a key 5¹ a longitudinal groove 4¹ in the said cylinder, so that it is driven on rotation of the cylinder 4, while the said longitudinal slot permits axial movements of the piston 5 in relation to the cylinder 4.

The piston 5 is rigidly connected by a rod 6 to the push member constructed as a push-bottom 7. Connected for rotation with this push-bottom 7, the diameter of which is such as to provide a small clearance with respect to the cage 1 by which it is surrounded, is a filling funnel 8. An axially displaceable control member 5² admits oil under pressure, delivered by a pump 5³ into a chamber 5⁴, alternately to the one or other side of the piston 5 which accordingly moves continuously backwards and forwards in the cylinder 4 during the rotation of the cage 1, imparting thereby corresponding movements to the push-bottom 7 and to the inlet funnel 8, so that these parts 7, 8 are moved axially in relation to the cage 1. The member 5² and the pump 5³ are both operatively connected to a motor 5⁵.

The material to be centrifuged flows out of a storage container 9 through a non-rotating feed pipe into the inlet funnel 8. The said feed pipe comprises a flexible portion 10 and a tube 11 rigidly connected thereto. The flexible portion 10 is secured to the container 9, and the tube 11 leads into the distribution chamber of the machine, the said distribution chamber being externally bounded by the funnel 8. This is an imperforate conical shell adapted to resist the entrance of atmospheric air. Situated between the delivery end of the tube 11 and that part of the funnel which surrounds the said end is a stuffing box 12 which forms a gas-tight and a liquid-tight seal between the funnel 8 and the delivery end of tube 11. The distribution chamber is thus substantially isolated from the atmosphere. A rod 7¹ is fixed at one end to the push-bottom 7 so as to rotate therewith and is mounted at the other end, which is fashioned as a disc 7² having convex surfaces, in a housing 7³ between two axial ball bearings 7⁴. The housing 7³ is secured to an extension 7⁵ of the tube 11. The tube 11 is thus forced to follow the axial movements of the rod 7¹ and consequently those of the push-bottom 7, which is rendered possible by the flexible portion 10 of the feed pipe. For these axial movements, rails 13 secured to the machine housing 13¹ serve as guides for the tube 11. For the sake of completeness, it is mentioned that the reference numeral 14 designates chambers which serve to collect the liquid forced through the sieve of the cage 1.

In the centrifugal machine described, the stuffing box 12 separates the distribution chamber in the interior of the machine, which chamber is filled with material to be centrifuged, in an air-tight manner from the atmosphere, so that no harmful ventilation can occur in this chamber. The stuffing box 12 also prevents ma-

terial to be centrifuged from passing into a trap 15 receiving the centrifuged material.

In order to prevent the setting up of a greater unbalance in the inlet funnel and to prevent the speed of flow therein from falling below a certain value dependent upon the material to be centrifuged, it is advisable to provide within the inlet funnel 8, and coaxially thereto as shown in Fig. 2, an inserted structure 16 having a filter screen 17. The mass of material contained in the funnel 8 can thus be reduced and better distributed. If such an inserted structure 16 with filter screen 17 is provided, a separation or pre-elimination of liquid can be effected in the chamber bounded by the inlet funnel 8 and the inserted structure 16, as indicated in horizontal chain lines in Fig. 2. This liquid can flow off through the filter screen 17. Alternatively, a tube 8¹ may extend into the said chamber for discharging the separated liquid. In this case, the outlet end of this tube 8¹ lies higher than the level of the material to be centrifuged which is stored in the container 9.

In order to prevent material to be centrifuged, which should pass through the stuffing box 12 provided at the entry of the feed pipe 11 into the inlet funnel, from passing into the trap 15, it is advisable, as shown in Fig. 3, to provide a supplementary funnel 19 outside the funnel 8, coaxially in relation thereto. These two funnels 19 and 8 define together a chamber 20 terminating in the neighbourhood of the outlet aperture of the funnel 8. Through this chamber 20 the leakage material passing through the stuffing box 12 can flow off into the separator cage 1.

Fig. 4 shows a form of construction in which a tube 22 of the feed pipe, extending into the distribution chamber of the machine, is pivotally mounted on the machine housing at one end at 23 and is spherically fashioned at the outlet end 24. This end separates, in conjunction with a correspondingly spherical surface of an intermediate ring 8² bearing against the inlet funnel 8, the distribution chamber of the machine in a gas-tight and liquid-tight manner from the atmosphere. The pressing force required for the tight bearing of the said spherical surfaces is produced by a spring 25 adjustable by a nut 25¹. This spring 25 bears at one end against the spherically-shaped part 7⁶ of the rod 7¹, which is provided with a joint 7⁸, and at the other end against a disc 7⁷ fixed to the rod 7¹. The parts 7⁶ and 7⁷ are enclosed in a housing 7⁹ provided on the tube 22.

Finally, Figs. 5 and 6 show a form of construction in which the feed pipe comprises a T-shaped link pin 28, 28¹ and a tubular portion 29 secured to the storage container 9. The vertical arm 28 of the link pin extends into the distribution chamber of the cage and the tubular portion 29 extends into the horizontal arm 28¹ of the link pin, there being provided at this leading-in point a stuffing box 33 sealing the interior of the feed pipe from the outside. Near to the discharge end of the substantially vertical arm 28 is provided a spherical surface 32 which is intended to co-operate with a correspondingly spherically fashioned surface of an intermediate ring 34 which bears against a hooked end of the inlet funnel 8, for the purpose of providing a gas-tight and fluid-tight seal at the points of contact between the spherical surfaces. The horizontal arm 28¹ of the link pin is pivotally mounted in two bearings 31 provided on the machine housing, so that

here again the portion 28, 28¹ of the feed pipe is able to follow the axial relative movements of the push-bottom 1, that is, of the rod rigidly connected thereto.

The operation of the centrifugal machine may be adapted in other ways to the quantity of material to be centrifuged arriving from a manufacturing plant, for example by varying the number of strokes of the pusher member per unit of time. For this purpose, for example, the delivery volume of the hydraulic pump 5³ shown in Fig. 1 and delivering the oil under pressure required for effecting the reciprocating movements of the pusher member 1 may be varied. This may be achieved, for instance, by constructing the motor 5⁵ driving the pump 5³ as a commutator motor allowing of varying the speed of the pump.

What is claimed is:

1. A continuously operable centrifugal machine, comprising a rotary driving shaft; a fo-raminous separator cage rigidly connected with said shaft; a housing enclosing said cage; a pusher member encircled by said cage and splined to said shaft so as to be shiftable in said cage in the direction of the shaft axis while turning with the shaft and cage; means for so shifting said pusher member; a flaring distributor shell connected with the pusher member so as to partake of the motions thereof and define therewith a distribution chamber isolated from the atmosphere by said shell, said chamber having an inlet on the axis of its rotation and a peripheral discharge adjacent said cage; a non-rotating pipe opening into said inlet; a fluid tight running seal between said pipe and distributor shell; and means associated with said pipe for accommodating the axial motion of said distributor chamber while maintaining said seal.

2. The combination defined in claim 1 in which the means associated with the pipe comprises right-line guides for the pipe, said guides being parallel with the axis of said shaft.

3. The combination defined in claim 1 in which the means associated with the pipe comprises an axis transverse to the shaft axis on which the pipe may rock and spherical and transverse sliding components in the running seal serving to accommodate the arcuate path of the pipe at the seal.

4. A continuously operable centrifugal machine, comprising a rotary driving shaft; a fo-raminous separator cage rigidly connected with said shaft; a housing enclosing said cage; a pusher member encircled by said cage and splined to said shaft so as to be shiftable in said cage in the direction of the shaft axis while turning with the shaft and cage; means for so shifting said pusher member; two spaced coaxial flaring shells connected with the pusher member so as to partake of the motions thereof and define therewith a distribution chamber separated from the atmosphere by the outer one of said shells, said chamber having an inlet on the axis of its rotation and a peripheral discharge from the annular space between the shells and adjacent said cage; a non-rotating pipe opening into said inlet; a fluid tight running seal between said pipe and said outer shell; and means associated with said pipe for accommodating the axial motion of said distributing chamber while maintaining said seal.

5. A continuously operable centrifugal machine, comprising a rotary driving shaft; a fo-raminous separator cage rigidly connected with said shaft; a housing enclosing said cage; a pusher member encircled by said cage and splined to said shaft so as to be shiftable in said cage in the direction of the shaft axis while turning with the shaft and cage; means for so shifting said pusher member; two spaced coaxial flaring shells connected with the pusher member so as to partake of the motions thereof and define therewith a distribution chamber separated from the atmosphere by the outer one of said shells, said chamber having an inlet on the axis of its rotation and a peripheral discharge from the annular space between the shells and adjacent said cage; a non-rotating pipe opening into said inlet; a fluid tight running seal between said pipe and said outer shell; means associated with said pipe for accommodating the axial motion of said distributing chamber while maintaining said seal; and a third flaring shell spaced from and encircling the first two shells and said running seal, and connected to rotate therewith, the last named shell being arranged to intercept leakage and deliver it to said cage.

6. A continuously operable centrifugal machine, comprising a rotary driving shaft; a fo-raminous separator cage rigidly connected with said shaft; a housing enclosing said cage; a pusher member encircled by said cage and splined to said shaft so as to be shiftable in said cage in the direction of the shaft axis while turning with the shaft and cage; means for so shifting said pusher member; a flaring distributor shell connected with the pusher member so as to partake of the motions thereof and define therewith a distribution chamber separated from the atmosphere by said shell, said chamber having an inlet on the axis of its rotation and a peripheral discharge adjacent said cage; a non-rotating pipe opening into said inlet; a fluid tight running seal between said pipe and distributor shell; means associated with said pipe for accommodating the axial motion of said distributor shell while maintaining said seal; and a flaring shell spaced from and encircling said distributor shell and said running seal and connected to rotate therewith, and being arranged to intercept leakage and deliver it to said cage.
